UNITED STATES PATENT OFFICE.

FRANK A. YOKOUM, OF SEATTLE, WASHINGTON.

MECHANICAL MOVEMENT.

SPECIFICATION forming part of Letters Patent No. 758,578, dated April 26, 1904.

Application filed March 21, 1903. Serial No. 148,996. (No model.)

To all whom it may concern:

Be it known that I, FRANK A. YOKOUM, a citizen of the United States of America, and a resident of the city of Seattle, in the county 5 of King and State of Washington, have invented certain new and useful Improvements in Mechanical Movements, of which the following is a specification.

My invention relates to improvements in 10 mechanical movements and has special reference to a manually-operative device of this class which is especially adapted for operation by hand.

Among numerous objects attained by this 15 invention and readily understood from the following specifications and accompanying drawings included as a part thereof is the production of a simplified and inexpensive mechanical motor embodying essential features of 20 adaptability, utility, and general efficiency, which render the device readily adjustable for reverse action, insures a positive uniform action, and transmutes manual energy into accelerated mechanical energy.

25 The above mentioned and other objects equally as desirable are attained by the constructions, combinations, and arrangement of parts as disclosed on the drawings, set forth in this specification, and succinctly pointed out 30 in the appended claims.

With reference to the drawings filed herewith, and bearing like reference characters for corresponding parts throughout, Figure 1 is a view in perspective of my improved mechanical motor as preferably embodied and adapted for the application of manual power to operate the same. Fig. 2 is a plan view of 35 the motor on reduced scale. Fig. 3 is a diagram showing the pitch-lines of the gears of the motor in relative position and the shafts therefor shown in vertical transverse section on line 3 3 of Fig. 2 looking as the arrows indicate and also shows the carrier for the drawing-wheels in relative position. Fig. 4 is a view in side elevation of the carrier on 40 large scale, and Fig. 5 is a view of the head of the carrier in transverse section on line 5 5 of Fig. 4 looking as the arrows fly.

This invention incorporates a driver, as 10, 45 which includes a pair of power-transmitting

wheels, as 11, each of which preferably consists of a spur-gear of comparatively large diameter, and these gears are suitably mounted for independent rotary movement on a shaft, as 12, conveniently disposed at one end of a 55 main frame, as 14, in a horizontal position and supported in suitable bearings, as boxes 15, mounted on the side pieces of the frame in any convenient manner. These transmitting-wheels are driven independently by 60 means of driving-wheels, as 16, which in the present embodiment comprise spur-pinions of comparatively small diameter which are suitably rotatably mounted in engagement with respective transmitting-wheels on a rotatable 65 carrier, as 17, which is suitably mounted concentric with said transmitting-wheels for reciprocal action, and as now considered includes three radially-disposed parallel arms 70 18 set at suitable separation to receive said 75 wheels loosely, and having suitable bearings, as 19, at the inner end adapted to rotatably support the carrier on shaft 12, whereby the carrier is conveniently supported concentric with said transmitting-wheels. At the outer 80 ends of these arms is secured a suitable head, as 21, which is adapted to tie the arms together, and this head is formed with suitable recesses, as 22, in the under surface to receive loosely the driving-wheels, and suitable apertures are formed in the end walls of these notches to conveniently afford bearings for the 85 axles, as 23, to which these driving-wheels are secured, and these bearings are arranged at suitable points to rotatably support the driving-wheels in engagement with the transmitting-wheels.

Suitable means are embodied with each driving-wheel 16 to lock it from rotation during movement of the carrier when operated in one 90 direction and allow said wheel to rotate freely when the movement of the carrier is reversed, so that reciprocal action of the carrier will be thereby transformed into continuous rotary movement of the transmitting-wheels through 95 the medium of respective driving-wheels when they stand locked.

As now considered, the means for locking the driving-wheels comprise rollers, as 24, one of which is associated with each of said wheels, 100

and these rollers are arranged in contact with the axles of said wheels in seats, as 25, formed longitudinally in the walls of the bores of the outer bearings for said axles. These seats for the rollers each comprise a notch or recess arranged longitudinally in said wall and formed with a semicircular base side substantially equal in radius to the radius of roller 24 so that the roller will be free to rotate when resting therein in contact with the axle of the driving-wheel, and the back side wall of this notch or recess is extended upwardly from the base at a substantially elliptical curve, which converges to the wall of the bore of the bearing, so that the roller will be thereby forced into positive binding contact with said axle when shifted laterally from the base of the seat, and thereby made to serve to lock the driving-wheel from rotation. As now considered oppositely disposed seats 25 are formed in the bore of the outer bearings for each of the axles 23, so that the rollers can be transposed in position to reverse the direction of rotation of the transmitting-wheels, and a suitable upwardly-extending handle, as 26, is conveniently removably seated in the head of carrier 17, by which the carrier is conveniently moved reciprocally to drive the transmitting-wheels.

30 By employing the rotatable driving-wheels the construction of such a driver is greatly simplified and a positive connection of the carrier with the transmitting-wheels is insured. Furthermore, the reversing of the application 35 of the driving power relatively to the transmitting-wheels is readily accomplished and the driver rendered capable of adjustment to drive the transmitting-wheels in the same or in opposite directions without requiring a great multiplicity of parts.

In the present embodiment suitable mechanism is embodied with the driver to concentrate the energy delivered by the transmitting-wheels, and as now considered this mechanism comprises a main shaft 27, supported 45 parallel to shaft 12 in suitable journals 28, a pinion 29, fixed to said shaft in mesh with one of the transmitting-wheels, a second pinion 33, also fixed to the shaft at one side of the other transmitting-wheel, and a pinion 31, rotatably supported in mesh with said second pinion and with last said wheel, and a suitable fly-wheel, as 32, is preferably fixedly mounted on shaft 27, and a power-transmitting wheel, as a 50 sprocket 38, is also fixed to said shaft.

As now considered the main frame 14 comprises end sills, as 34, side pieces 39, secured upon said sills, and a beam 35 intermediate said side pieces and secured to said sills and the 60 journals for the main shaft, and the bearings for the shaft 12 of the driver are mounted on the side pieces of this frame, while a bearing-box, as 36, is arranged on the beam 35 to support one end of an axle, as 37, for the intermediate pinion 31, while the opposite end of

said axle is suitably supported by forming an aperture in the adjacent side piece of the frame to receive same.

Granted construction of such a motor, an operation thereof would occur substantially as follows: The rollers 24 are first disposed in respective seats which lie opposite, as shown in Fig. 5, and the carrier is then forced to move—for instance, to the left, as viewed in Fig. 1. This will cause both driving-wheels to rotate until the roller shown on the left in Fig. 1 is raised in its seat by action of respective axle 23, and thus brought to bind upon said axle and lock the respective driving-wheel, when the respective transmitting-wheel will be forced to rotate with the carrier, while the roller at the opposite side of the machine will remain in the base of its seat and rotate with the axle of its respective driving-wheel until the movement of the carrier is reversed, when this roller will then be forced into binding position and the opposite roller carried to the base of its seat by the reverse action of the axle with which it contacts. Thus the transmitting-wheels will be driven in opposing directions and serve to drive the main shaft of the concentrating mechanism continuously in one direction through the medium of the pinions secured thereon and the intermediate pinion.

95 This motor is simple of construction, positive in action, and has few parts likely to get out of order, and can be employed in numerous places where a motor of this class would be useful—as, for instance, it can be used to 100 drive rotary fans, hand-cars, boat-propellers, wheeled vehicles, and numerous other mechanism requiring the application of driving power.

Having thus described my invention, what I claim as new, and desire to secure by Letters Patent of the United States of America, is—

1. In a mechanical movement of the nature indicated; a driver comprising rotatably-mounted power-transmitting wheels, a reciprocally-rotative carrier mounted concentric with said wheels, driving-wheels rotatably mounted on said carrier in engagement with said transmitting-wheels, and transposable means to lock said driving-wheels from rotation in one direction.

2. In a mechanical movement, a pair of power-wheels, an oscillatory carrier common to both wheels, means for transmitting motion from the carrier to the wheels, and means carried by the carrier and acting in conjunction with the transmitting means whereby the power-wheels may be operated independently or simultaneously.

3. In a mechanical movement of the nature indicated; the combination of a rotatably-mounted power-transmitting wheel, a reciprocally-rotative carrier mounted concentric with said wheel, an axle rotatably mounted in said carrier, a driving-wheel fixed to said axle

in engagement with said transmitting-wheel, an axle-locking roller disposed longitudinally said axle in contact therewith, there being oppositely-disposed seats for said roller opening 5 to said axle and formed with the back side walls extending upwardly and curving toward said axle.

4. In a motor of the nature indicated; a driver comprising rotatably-mounted power-transmitting wheels, a reciprocally-rotative carrier mounted concentric with said wheels, driving-wheels engaged with said transmitting-wheels, independently-rotatable driving-wheel axles journaled on said carrier, an axle-locking roller for each of said axles, there being oppositely-disposed seats for said rollers formed in the wall of the bore of the axle-journals and comprising recesses formed with semicircular bases adapted to removably receive said rollers in contact with said axles and upwardly-extending back side walls curving inwardly toward said axles.

5. In a motor of the nature indicated, a driver comprising a shaft 12, power-transmitting wheels 11 rotatably mounted on said shaft, a reciprocative carrier 17 rotatably mounted on said shaft, driving-wheels 16 engaged with said transmitting-wheels, axles for the driving-wheels journaled on said carrier, there being oppositely-disposed roller-receiving seats 25 in the walls of the bores of the journals of said axles, and axle-locking rollers 24 removably fitting in said seats.

6. In a motor of the nature indicated; a driver comprising a supported shaft, power-transmitting wheels comprising spur-gears ro-

tatively mounted on said shaft, driving-wheels comprising spur - pinions engaged with the teeth of said transmitting-wheels, a reciprocal carrier comprising a head having notches 40 adapted to receive said pinions and having apertures in the end walls and radially-disposed arms secured to said head and having bearings at the inner ends on said shaft, an axle for each of said driving-wheels rotatably mounted 45 in said apertures, there being oppositely-disposed roller-seats in the walls of the outer of said apertures each formed with a semicircular base and an upwardly-extending back side wall curving toward said aperture, and an 50 axle-locking roller for each pair of said seats.

7. A motor of the nature indicated, comprising rotatably - mounted power - transmitting wheels, a reciprocally-rotative carrier mounted concentric with said wheels, driving-wheels independently rotatably mounted on said carrier in engagement with said transmitting-wheels, transposable means to lock said driving-wheels from rotation in one direction, a rotatably-mounted main shaft, a pinion fixed 60 on said shaft in engagement with one of said power-transmitting wheels, a second pinion fixed on said main shaft and a rotatably-mounted intermediate pinion engaged with said second pinion and with the other trans- 65 mitting-wheel.

Signed at Seattle, Washington, this 22d day of February, 1903.
